WISCONSIN, A CORPORATION

ELECTRIC-LIGHT FIXTURE

Application filed March 22, 1929. Serial No. 349,235.

This invention pertains to an electric light fixture, and more particularly to that type commonly known as an indirect light, wherein the rays of light from the incandescent bulb are reflected against the ceiling or other reflecting surface.

The present invention, which is applicable to any type of fixture, such as a pedestal lamp, or a wall or ceiling bracket, has primarily for its object the provision of a simple, inexpensive, and efficient fixture assembly which eliminates securing means, such as rivets, bolts, and the like, and which insures proper centering of the focal point of the light with relation to the parabola of the reflector.

Incidental to the foregoing, a further object resides in the provision of a fixture in which the reflector constitutes the shade and is held in assembled position on the bracket or standard by means of the light bulb.

A more specific object resides in the provision of a detachable sleeve for engaging the reflector and cooperating with the light bulb for rigidly securing the reflector to the standard and properly centering the light with relation to the reflector.

With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawing, the single view is an elevation of a fixture constructed in accordance with the present invention, with parts broken away and in section to more clearly illustrate structural details.

Referring now more particularly to the accompanying drawing in which the invention is shown as applied to a pedestal floor lamp,

the numeral 1 designates a standard of any conventional structure or design, and while the same is described as a pedestal, such description is meant to include a supporting bracket of any type, adapted to be mounted upon a wall or ceiling, although where employed in residences, the greatest advantage from the indirect light is to be derived from a floor lamp which may be conveniently moved to the most desirable position to give the maximum amount of light.

Mounted on the end of the standard 1 is an elongated cup 2 which houses a conventional light socket 3. The upper end of the cup 2 is flared at 4 for the reception of a reflector bowl 5, which merely seats thereon. Obviously, the interior of the reflector bowl may be finished in a highly polished reflecting surface, while the exterior may be finished in any color desired. Thus, it will be seen that the bowl 5 serves as both a reflector and a shade, which reduces the cost of manufacture to a minimum.

As disclosed in the drawing, the flared mouth 4 of the cup 2 serves as a seat for the reception of the reflector bowl 5, and for the purpose of clamping the reflector on the cup in assembled position, an adaptor 6 is provided, which comprises a sleeve provided with a flared upper edge 7 and an annular extension 8, preferably formed by crimping the material of the sleeve intermediate its ends.

As best shown in the drawing, the reflector bowl 5 is provided with a central aperture 9 which receives the lower end of the adaptor 6, and the annular extension 8 serves to support the adaptor in assembled position.

For clamping the reflector bowl 5 on its seat, the conventional incandescent bulb 10 is inserted through the adaptor 6, and threaded into the socket 3, in the usual manner; and in this position, it is obvious that the enlarged portion of the bulb 10 will engage the flared end of the adaptor 6 and securely clamp the reflector bowl on the cup, thus eliminating the necessity of bolts, screws, or other forms of securing means, and greatly facilitating the assembling operation of the various parts.

A further advantage of the present structure resides in the fact that although a slight variation in the position of the socket 3 may occur, the adaptor 6 absolutely insures proper centering of the lamp 10 with relation to the parabola of the reflector, which, in turn, maintains the focal point of the light in the desired position to obtain maximum efficiency from the reflector.

In some instances where it may be desired to employ the fixture for either indirect or direct lighting, or both, the cup 2 may be provided with auxiliary brackets 11 which carry conventional lamp sockets 12 for the reception of the bulbs 13. This permits the lamp to be used for direct lighting and adds materially to its attractiveness when the indirect light is not in use.

From the foregoing description, taken in connection with the drawing, it will be readily seen that an exceedingly simple, inexpensive, and efficient structure has been provided, in which the parts are readily assembled without the use of rivets, screws, or other securing means, and which can be readily disassembled for shipping purposes.

While the adaptor 6 is shown as separate and distinct from the reflector bowl 5, it will be appreciated that the same may be formed integral therewith without departing from the spirit of the present invention. However, the present structure is considered preferable at this time for various manufacturing reasons.

We claim:

1. An electric light fixture comprising a standard, an elongated cup carried by said standard and provided with a flared mouth forming a seat, a light socket housed within said cup, a reflector bowl seated on the flared mouth of said cup and provided with a central aperture disposed in said mouth, a sleeve mounted in said aperture, and a light bulb threaded into said socket and engaging said sleeve for clamping said reflector bowl on its seat.

2. An electric light fixture comprising a standard, an elongated cup carried by said standard and provided with a flared mouth forming a seat, a light socket housed within said cup, a reflector bowl seated on the flared mouth of said cup and provided with a central aperture disposed in said mouth, a sleeve mounted in said aperture, said sleeve having a flared upper end, and a light bulb extending through said sleeve and threaded into said socket for clamping said reflector bowl on its seat, the flared end of said sleeve engaging the enlarged portion of said bulb.

3. An electric light fixture comprising a support, a reflector bowl, a cup carried by the support having a flared mouth forming a seat for the reflector bowl, said seat conforming to the curvature of the bowl, where-
65 by the bowl can be received in said seat in

different angular positions, a light socket housed within said cup below the reflector bowl, a light bulb threaded into the socket and means carried by the reflector bowl and receiving a part of the light bulb for centering the light bulb in the reflector bowl.

In testimony that we claim the foregoing we have hereunto set our hands at Milwaukee, in the county of Milwaukee and State of Wisconsin.

STANLEY M. HALLAM.
ROBERT E. HINE.
